UNITED STATES PATENT OFFICE.

HENRY K. AUSTIN, OF READING, MASSACHUSETTS, ASSIGNOR TO HIMSELF AND NATHAN BANCROFT, OF SAME PLACE.

EXHAUST-NOZZLE FOR LOCOMOTIVES.

SPECIFICATION forming part of Letters Patent No. 240,071, dated April 12, 1881.

Application filed January 29, 1881. (No model.)

To all whom it may concern:

Be it known that I, HENRY K. AUSTIN, of Reading, in the county of Middlesex and State of Massachusetts, have invented certain Improvements in Exhaust-Nozzles for Locomotives, of which the following is a specification.

This invention relates to that class of exhaust nozzles or tips for locomotives so constituted that the discharging area or outlet of the exhaust-pipe may be varied at the will of the engineer for the purpose of freeing his engine when desired, and is an improvement on the variable-exhaust patent of A. S. Smith, No. 125,414, issued April 9, 1872.

The invention consists, first, in a nozzle or tip of peculiar and novel construction, whereby greater perfection of action is secured; and, secondly, in the provision of means for operating said tip from the cab of the locomotive, all of which I will now proceed to specifically describe, reference being had to the accompanying drawings, forming part of this specification, in which—

Figure 1 represents a vertical section of a nozzle or tip embodying my invention. Fig. 2 represents a top view of same. Fig. 3 represents a side view of a portion of a locomotive, showing part of the mechanism employed in operating a nozzle embodying my invention.

Fig. 4 represents a top view of the same, showing also the additional mechanism required. Fig. 5 represents a front view of the mechanism shown in Fig. 4; and Fig. 6 represents a similar view, exhibiting a modification of my invention.

In these several figures similar letters of reference refer to the same parts.

In the drawings, A represents a metallic nozzle or tip, tubular in form, and adapted to be rigidly connected with the exhaust-pipe of a locomotive-engine. The vertical wall of the tip A is carried outwardly at a', thus enlarging the area of the tip and forming a chamber, c c, within the same. Above the chamber c c the vertical wall of the tip is carried inwardly with an abrupt inclination to meet the top of the tip a'. In the inclined portion of the ver-

tical wall thus produced a series of ports or orifices, d, are formed entirely around the tip.

f represents a flange entirely surrounding the tip and rigidly secured to the same by bolts.

In the intervening annular space formed between the flange f and the upper part of the vertical wall of the tip I place a register, consisting of a series of plates, d', formed upon a flange, e. These plates d' correspond in number and size to the ports d, and the register rests upon the outer surface of the inclined portion of the vertical wall of the tip, and is adapted to be partially rotated, so as to bring the plates d' over the ports d, and thus close the latter. The register is confined in position within the annular space surrounding the tip by means of a lip, i, formed on the flange e, and entering a corresponding groove or depression in the inner side of the flange f, the flange f being adapted to be secured to the tip after the register has been placed in position. The register is rotated and the ports d opened or closed by means of an arm, h, formed upon the flange e or rigidly connected with the same and suitable operating mechanism communicating with the cab of the locomotive, and shown in Figs. 3, 4, 5, and 6. Said operating mechanism consists of a shaft, s, extending horizontally through the side of the smoke-stack arch, a crank, p³, attached to the outer end of said shaft, a connecting-rod, r³, connecting the crank p³ to the lift-arm of the locomotive, (said lift-arm being connected, as usual, to the reverse-lever l in the cab C by a rod, r'), and suitable intermediate mechanism connecting the shaft s with the arm h of an exhaust-nozzle in the smoke-arch, or with the arms of two nozzles when a double tip is used, as shown in Fig. 4.

Two forms of intermediate mechanism are shown. In the construction shown in Fig. 4 the shaft s has a bevel-gear, g, meshing with a similar gear, g', upon the vertical shaft s' within the smoke-chamber. An arm, n, upon the shaft s' is connected by means of the link n' with the rod m. The extremities of the rod

m are connected with the arms *h h* of the nozzles or tips *A A*, placed in position over the exhaust-pipes of the locomotive. The gears *g g'* are protected from dust, cinders, &c., by a 5 tight cast-iron casing, *K*. (Shown in Fig. 4.)

By means of the described mechanism the movement of the lever *l* is transmitted to the arms *h h* and the register of the tips *A A* partially rotated, thus opening or closing the ports *d* in 10 said tips. The aforesaid mechanism is so adjusted that when the lever *l* is on the center, as shown in the figures, and the engine standing still, the ports *d* are closed. When the lever *l* is moved forward or backward the ports 15 are opened.

The described connection of the exhaust nozzles with the reverse-lever prevents the engineer from neglecting to operate the register and vary the discharge-opening of the nozzles.

20 If desired, however, the rod *r'* may be disconnected from the lift-arm, and the exhaust may be opened or closed by means of the rod *r''*, one extremity of which is attached to the crank *p*, and the intermediate mechanism connected 25 with the arms *h h* of the nozzle-register, and the other extremity attached to the lever *h'*, secured to the inner wall of the cab by means of the link *l'*. The lever *h'* is provided with a self-shooting bolt adapted to engage with 30 notches in an arm, *t*, attached to the wall of the cab, thus locking the lever and the registers of the exhaust-tips in any desired position.

In the modification of my invention shown in Fig. 6 I substitute for the cogs *g g'* and 35 other intermediate mechanism connecting the pivoted crank *p* with the register-arms *h* the vertical rotary shaft *o*, having thereon an arm, *x*, connected with the crank *p* by a link, *x'*, pivoted to the shaft *s*, and also having an 40 arm, *x''*, pivoted to the link *n'*, which is connected with the arm *h* of the nozzle-register. The movement of the crank *p* partially rotates the shaft *o*, and the arm *x''* thereon acts to open or close the register by means of the link 45 *n'*, connected therewith.

The operation of my invention will be readily understood from the foregoing description.

When the locomotive is at rest the ports *d* are closed, the lever *l* being then on center, as 50 above stated. When the locomotive is started and the lever *l* moved forward, the ports *d* are opened, thus enlarging the discharging area of the exhaust-pipe and giving a freer outlet of steam at the time when such outlet is most 55 required. The same result is effected by moving the lever *l* back when the movement of the engine is reversed.

My improved form of nozzle herein described 60 presents several important advantages over any nozzle of this class with which I am acquainted, inasmuch as by placing the register substantially upon the top of the nozzle instead of inclosing the same, and resting said register upon an approximately horizontal seat,

65 I am enabled to use a narrow register and a

corresponding narrow register-seat. This therefore reduces to the minimum the rubbing-surfaces, overcoming friction and liability to corrosion. The abrupt inclination of the upper part of the wall of the nozzle—approximately horizontal—allows the ports to be made large, and affords a direct upward outlet for the escaping steam passing through the nozzle from the exhaust-pipes, while at the same time the nozzle can be made as short as desired. 70 The vertical flange *e* of the register and the vertical flange *f* outside it cause any steam that may escape between the register and the flange *f* to issue upwardly, preventing all lateral leakage of escaping steam, such lateral 75 leakage sometimes occurring in the ordinary form of nozzle, being liable to deaden the draft in the smoke-arch, besides creating moisture which mixes with the cinder and produces 80 crustations and rust upon the surfaces of the smoke-arch.

When a single nozzle or tip of the ordinary form is used upon the exhaust-pipes, there is a liability of the exhaust-steam from one cylinder entering the other cylinder and creating 90 back-pressure when the ports are closed. This is obviated in my invention by the formation of the chamber *c c* within the nozzle, thereby affording more space for the escaping steam and preventing back-pressure.

Having thus described my invention, I claim—

1. The tip *A*, having its upper portion inclined inwardly to form an approximately horizontal seat, containing the ports *d*, and provided with the vertical fixed flange *f* outside of said seat, combined with the movable register *d'*, resting upon said seat and provided with the vertical flange *e*, bearing against the inner vertical surface of the fixed flange *f*, substantially as shown and described. 105

2. The improved variable-exhaust nozzle, composed of the tip *A*, having the central steam-inlet, *c'*, at its base, the approximately horizontal seat provided with ports *d* and main outlet *a'* at its top, the intermediate enlargement or chamber, *c*, the vertical flange *f*, and the movable register on said seat, all constructed and operated substantially as described. 110

3. A nozzle for locomotive exhaust-pipes having a chamber formed within the same by enlargement of the tube, and having approximately horizontal ports over said chamber, said ports being adapted to be opened or closed by a register rotating within an annular space around the top of the nozzle, as set forth. 115

4. The herein-described means for operating a nozzle for exhaust-pipes, consisting of the connecting-rod *r'*, connected with the lift-arm *p*, rod *r*, and reverse-lever *l*, and with the arm *h* of the nozzle-register, by suitable intermediate mechanism, the whole acting to open and close the ports of the nozzle, as set forth. 125

5. The described means for operating a noz- 130

zle for exhaust-pipes, consisting of the rod r^2 , connected with the nozzle-register by means of the arm h , the crank p^3 , and suitable intermediate mechanism, the other extremity 5 of said rod r^2 being connected with a lever, h' , pivoted to the wall of the cab by means of the link l^4 , and provided with locking mechanism, whereby the exhaust register or registers are locked in any desired position, as set 10 forth.

In testimony whereof I have signed my name to this specification, in the presence of two subscribing witnesses, this 22d day of January, A. D. 1881.

HENRY K. AUSTIN.
